W. A. RUPPERT.

VESSEL FOR FREIGHT OR PASSENGERS.

APPLICATION FILED SEPT. 9, 1912.

1,089,674.

Patented Mar. 10, 1914.

UNITED STATES PATENT OFFICE.

WILLIAM ALBERT RUPPERT, OF NEW YORK, N. Y.

VESSEL FOR FREIGHT OR PASSENGERS.

1,089,674.

Specification of Letters Patent. Patented Mar. 10, 1914.

Application filed September 9, 1912. Serial No. 719,200.

To all whom it may concern:

Be it known that I, WILLIAM ALBERT RUPPERT, a citizen of the United States, residing in the borough of Manhattan, in the city and State of New York, have invented a certain new and useful Improvement Relating to Vessels for Freight or Passengers, of which the following is a specification.

It may apply usefully to a wide range of sizes of vessel. I will describe it as on a large vessel built of wood and intended mainly for the accommodation of passengers. The invention can be better applied in the act of originally building of the vessel but it may serve with a little more expense on vessels already completed.

I have devised a way to store in the bottom or sides of the interior of a vessel, flexible air tight bags with flexible hose, connected with protections which afford a fine finish, opening outward with gentle force. I provide means for inflating each bag independently at will and I employ an engine adapted to serve the double duty of pumping air rapidly into these bags when required and of performing other work when all is proceeding well. I provide for controlling from a single point as the wheel house or bridge the delivery of air to the several bags and preventing its reflow. I also provide for preventing the loss of much air if any bag shall be ruptured.

The following is a description of what I consider the best means of carrying out the invention. The accompanying drawings form a part of this specification.

Figure 1 is a diagram in side elevation with a portion broken away to show the interior. Fig. 2 is on a larger scale. It is a cross section on the line 2—2 in Fig. 1. Fig. 3 is a plan view on the line 3—3 in Fig. 2. Fig. 4 is a horizontal section of a detail on a still larger scale, and Fig. 5 is a vertical section of a portion of a bag in its folded condition.

Similar letters and marks of reference indicate corresponding parts in all the figures where they appear.

A is the hull of the vessel—A' the main deck and A² a lower deck. Either deck is capable of holding up the vessel and its freight when it is itself supported in case of disaster by the means now to be described.

55 I make in the interior of the vessel any desired number of shallow recesses and par-

tially conceal each with a slightly fastened cover E of wood adapted to form a finish. I secure these covers by specially slight fastenings G, adapted to hold them sufficiently against ordinary disturbing agencies when the vessel is rolling, and reliably against slight forces in any direction, but weak in the direction which bounces the bag out of its recess. It is always ready in an emergency to move bodily and liberate the contents with ease. These shallow spaces for the bags may be on specially erected supports and they will be so shown. A² are the raised edges of these spaces or recesses—a, which hold these compacted floats ready for constant service.

B are flexible bags of air-tight material—B' an air-tight valve opening inward. There is a spring not shown holding it strongly and reliably closed but ready to yield to allow air to enter the bag and be well retained.

C is a main pipe extending lengthwise of the vessel branched as required, C'—C' are such branches. These will be referred to more fully below.

D is an efficient air-compressing pump and a driving motor with the necessary parts for starting and maintaining the action. One of the duties for which this air pump is equipped is to drive air at only a little above its usual pressure through the pipes C and its branches and inflate all the bags B which it is allowed to reach.

The bags are folded in large folds. The thin parcels thus formed may be curved to match in curved spaces in the vessel but they lie usually nearly flat. In the process of manufacture or afterward before placing the bags in connection in the vessel, each fold in the several bags is defended against the formation of cracks in the folds by inclosing therein short lengths of what I will term a "packing," a soft rope of gently twisted cheap fiber as the fine wood shavings much used in packing, known as "excelsior." Such a soft and accommodating defense P extends along the inner face of what would otherwise become a sharp fold in each bag and insures that the sharpness of the fold shall be greatly softened and the time which the several bags will last without cracking at the folds shall be greatly prolonged.

The covers E of spruce or other light wood are made to extend across the recep-

tacles *a*. I prefer that these recesses and the bags which match loosely in them shall be of such size that the covers may in the management of the vessel be detached and used for other purposes when all is going well.

5 In the "double-deck" vessel shown in the figures, several of these receptacles and their covers are shown in positions where they may serve as tables. It will be understood that others are in the ceiling of the 10 "between-decks," others in the floor of the between-decks and others may be on edge in any of the upright faces in the interior of the vessel. In the construction of a new 15 vessel the places may be provided for more than will be always needed, and in fitting out for a voyage only so many of the bags and hose may be supplied as are judged expedient for that voyage. When certain recesses are not used for bags the covers *E* 20 may obviously be omitted there.

The hinges for the covers *E* are of the well-known kind easily separable by removing the pin, so that while in ordinary use 25 they are ready to maintain the desired hinged connection and allow the cover to rise and sink, controlled only by the hinges and by gravity and the slight strings which are easily breakable, they can also be conditioned with little labor to allow the cover 30 to be completely detached.

The series of pipes and hose *C* with efficient controlling valves extends lengthwise of the vessel with a separate branch to 35 each bag. These perform the main duty of flowing air at gentle pressure to inflate each bag with the effect first to get it out of its recess and next to fill it with air to the large extent required.

40 A set of small hose pipes *J*, one for each bag extend from the air-reservoir *H* past the wheel-house or other desired point for a skilful and diligent officer to stand and afford means of control. If the vessel as is 45 often the case inclines to be too much down by the head or by the stern or to heel over to either side, this control allows the vessel to be held very nearly upright by effecting the inflation of only the required bags. The 50 details for this important control are simple. Each bag *B* has a valve *B'* (see Fig. 3) which is self-acting, opening in the direction to fill the bag with air. In the absence of any movement by the officer in the 55 wheelhouse, the large air-pump *D* being started all the bags get wind and all become under ordinary conditions about equally inflated. If the vessel is much out of level there will be interference by the officer in 60 the wheel-house, he simply presses the proper keys *I* and arrests the current of air through such of the small pipes *C'* as he sees fit. The pressure on any one of the 65 keys *I* cuts off the air pressure supplied through the pipe *H'* and the individual

70 pipes *J* to the respective pistons *M* in the cylinders of the valves *K* and allows the spring *L* in the valve so cut off to force the piston *M* upwardly and thereby carry the aperture *m* out of line with the sections of 75 the pipes *C'* (see Fig. 4), thus shutting off all communication with the corresponding bag *B*. The pump *D* which supplies the air to flow through the hose *C* and the valves *B'* may be large, adapted to drive large 80 quantities of air to fill all the spacious bags rapidly and still require but a small steam cylinder to drive it because there is but little resistance to the early inflation of the bags. The water is supposed to be rapidly rising but has not yet covered the bags and only gentle pressure of air is required within the pipe *C* to promptly break the slight fastenings *G* and push away the covers *E*. If the water did not rise to that level 85 the bag will be on the floor. If on the contrary the emergency is more advanced the bag will float, and in any case, there must always be sufficient length of hose to allow each bag to rise until it bears against something as the under side of a deck above, thereafter contributing efficiently to the uplift of the vessel and its "even keel."

90 In the ordinary use of the invention, common air gently compressed will swell the bags and break the fastenings of their several recesses and float the vessel indefinitely. The slight fastenings *G* which may be small 95 lead wires should always be in plain sight and be often inspected and kept in order 100 ready for immediate work. Before the order is given to start the steam pump *D* and commence the inflation a preliminary order may remove the fastenings *G* and we can then effect the commencement of the inflation by a 105 lower pressure of the air. If this is a step in serious business but found later to be not wanted, it is easy to refold the bags and to place them in their receptacles and by slight 110 strings to lightly refasten the covers again 115 until the vessel arrives where more material and skilled help will restore the easily inflatable condition.

120 The drawing Fig. 2 shows in strong lines four folded bags, each in a horizontal plane 115 with a cover *E* hinged at one side to the bulkhead and capable of rising to liberate the bag at the other side. The lifted position is shown in one on the lower deck in dotted lines. Another arrangement may be to hold the folded flat parcels overhead. In such form of the invention the shallow recesses *a* in which they sit are in the ceiling and hold the bags therein each in a horizontal flat parcel. They may be in any positions found convenient in any particular style of vessel.

125 Modifications may be made without departing from the principle or sacrificing the advantages of the invention. Other means 130

of safety may be used in addition to these. The covers when of wood may be used to form rafts and thus aid to leave the vessel. In parts of some vessels, as under the lower berth in a cabin, the covers may be dispensed with and the rightly folded and connected bags may lie absolutely free and in sight or concealed only by a curtain ready to slowly or rapidly emerge and rise when the air is received.

10 The same apparatus if its use is postponed until after the vessel has sunk to the bottom may be yet of important service. In addition to any other means applied of raising 15 the vessel and holding her supported while the tow travels with her to a convenient harbor, my bags and connections may be made of use with sufficient power at command by sending a diver down and having him make 20 a tight connection to the reservoir and then by a fireboat or other vessel assisting, sending down air through the hose thus combined. At any moderate depth this invention may be worked in this way.

25 Parts may be used without the whole. Additions may be made. The controlling pipes J may be larger than shown.

I claim as my invention:

30 1. A vessel having partially inclosed receptacles of little depth distributed in its interior, flexible air-tight bags correspond-

ingly distributed, said receptacles holding such bags compactly folded and also maintaining provisions through which each bag may easily escape on being expanded with 35 air, pipes arranged to connect the whole or any part with air-supplying means, and mechanism controllable from a single point adapted for directing the air into any bags as required.

2. In air-tight bags for floating vessels folded compactly for storage on the vessel each independently of the others, yielding cushions serving for packing, in the interiors of the folds, arranged to cause the material 45 to curve and avoid being sharply folded.

3. A vessel, a series of air-tight bags therein, a reservoir and hose to carry air under gentle pressure to the whole of the series or to a part thereof as desired, one valve for 50 each bag adapted to work when liberated at a distant point and deliver air into the bag and prevent its return, and another valve for each bag of a construction adapted to resist automatic delivery in either direction, 55 a spring tending to move the latter valve and provisions for moving such valve against the pressure of the spring at will.

WILLIAM ALBERT RUPPERT.
